UNITED STATES PATENT OFFICE.

HUGO BORCHARDT, OF CHARLOTTENBURG, GERMANY.

BREECH-MECHANISM LOCK FOR AUTOMATIC FIREARMS.

1,071,028.

Specification of Letters Patent.

Patented Aug. 26, 1913.

Application filed August 16, 1911. Serial No. 644,318.

To all whom it may concern:

Be it known that I, HUGO BORCHARDT, a citizen of the United States of America, residing at No. 31 Kantstrasse, Charlottenburg, Germany, have invented new and useful Improvements in Breech-Mechanism Locks for Automatic Firearms, of which the following is a specification.

The invention relates to a breech mechanism lock for automatic firearms, which is brought into the locking position by the cartridge feed device.

The object of the invention is mainly differentiated from the known breech mechanism locks in that when the magazine is empty the locking device causes the closing action of the closing spring upon the breech block to cease. This spring may also exert a braking action upon the breech block by 20 the intermediary of the locking device.

An embodiment of the invention is illustrated by way of example in the accompanying drawing, in which:

Figure 1 shows the rear portion of the 25 weapon in side elevation partly in section with the breech closed immediately before the last cartridge is fired. Figs. 2 to 4 are fragmentary vertical longitudinal sections illustrating different positions of the locking device to a larger scale, Fig. 2 in a position corresponding to Fig. 1, Fig. 3 with the breech open after the last cartridge has been fired and Fig. 4 in the same position with the locking spring engaged. Fig. 5 illustrates a modification, in which the locking device does not exert a braking action, but is shown in a position corresponding to Fig. 4.

The invention is shown applied to a 40 weapon in which the opening and closing movement of the reciprocating breech block is effected by the pivoted levers *h* *i* and the breech closing spring *f*. The spring *f* which is mounted beneath the breech casing and guided on a rod *e* with collar *e'* is coupled 45 with the rear lever *i* by means of a link chain *g* for the purpose of obtaining this breech closing action.

Beneath the guide path of the breech block behind the magazine the two-armed lever *b* is rockably mounted on the pivot *c* in a recess in the breech casing; the front arm *b'* of this lever protrudes into the magazine through the rear wall of the magazine casing. The feed device *z* comprises at its

rear part a projection *z'* which, when the 55 magazine is empty engages beneath the portion of the lever arm *b'* which projects into the magazine so that the lever *b* leaves its normal position (Fig. 2) in which it is held by the spring *d* (which acts upon a nose *b''* 60 on the lever) and assumes the locking position (Figs. 3-5) under the influence of the more powerful feed device spring *z''*. The rear arm *b''* of the lever *b* is bent downward the projecting nose *b''* forming a 65 shoulder *b'''* on the lower side of this arm and when the lever is moved into the locking position this shoulder projects into the path of the collar *e'* on the spring guide rod *e*. Consequently at the beginning of the closing 70 movement of the breech block the collar *e'* comes behind the shoulder *b'''* so that the lever *b* itself interrupts the further movement of the locking spring and consequently the action of the spring on the levers *h* *i* and 75 the breech block in the sense of closing the breech. The closing spring then holds the lever in the locking position. When a fresh magazine has been inserted in place the lever *h* can be released by drawing back the 80 breech block, so that under the pressure of the spring *d* this lever rocks out of the path of the locking spring.

The lever *b* can be formed in such a manner that the locking action of the closing 85 spring on the breech block is eliminated (Fig. 5) or else so that the closing spring is caused to exert a braking action upon the breech block by the intermediary of the lever *b* (Fig. 4).

In the former case the breech block can 90 readily be displaced by hand with the closing spring engaged. This arrangement is of especial advantage when the breech block is to be stopped at a given point, for example for charging the magazine. In this case it is preferable to provide a special retaining device (not shown) for the breech block. If, however, the closing spring is also required to exert a braking action upon 95 the breech block, the front lever arm *b'* is formed as a braking arm. This braking arm *b'* is then pressed against the breech block in the direction of the arrow *b'* by the closing spring acting upon the lever arm *b''* 100 (Fig. 4), thus braking the block. The braking action can be rendered stronger or weaker by suitably forming the lever *b*.

What I claim and desire to secure by Letters Patent of the United States is:

1. Breech mechanism for automatic firearms comprising, a magazine, a breech block, a closing spring for said breech block, a cartridge feed device, and means under control of said cartridge feed device adapted to engage said breech closing spring when said magazine is empty, said breech block being free to move forward when said spring is locked. 60
2. Breech mechanism for automatic firearms comprising, a magazine, a breech block, a closing spring for said breech block, a cartridge feed device, and means under control of said cartridge feed device adapted to engage said breech closing spring to interrupt its closing action on said breech block when said magazine is empty, said breech block being free to move forward when said spring is locked. 65
3. Breech mechanism for automatic firearms comprising, a magazine, a breech block, a closing spring for said breech block, a cartridge feed device, means under control of said cartridge feed device adapted to engage said breech closing spring and operated by said spring to exert braking action upon said breech block. 70
4. Breech mechanism for automatic firearms comprising, a breech block, a closing spring for said breech block, a cartridge feed device, and breech block braking means under control of said cartridge feed device 75
- adapted to engage said breech closing spring. 90
5. Breech mechanism for automatic firearms comprising, a breech block, a closing spring for said breech block, a cartridge feed device, a pivoted lever under control of said cartridge feed device adapted to engage said breech closing spring, and a surface on said lever adapted to exert braking action on said breech block. 95
6. Breech mechanism for automatic firearms comprising the combination with a breech block of a closing spring for the said breech block, a cartridge feed device and a pivoted lever one arm of which projects into the magazine and by the other arm engaging the said breech closing spring when the magazine is empty. 100
7. Breech mechanism for automatic firearms comprising the combination with a breech block of a closing spring for the said breech block, a cartridge feed device arranged in the magazine and a pivoted lever one arm of which projects into the magazine the other arm being bent downwardly and 105
- having a shoulder thereon said shoulder co-acting with the said breech block closing spring when the magazine is empty. 110
8. Breech mechanism for automatic firearms comprising the combination with a breech block of a closing spring for the said breech block, a cartridge feed device, a pivoted lever one end of which projects into the path of said cartridge feed device the other end being bent downwardly and having a shoulder thereon which engages the said breech closing spring when the magazine is empty and a spring for holding the pivoted lever out of engagement with the breech closing spring when the magazine is not empty. 115
9. Breech mechanism for automatic firearms comprising the combination with a breech block of a closing spring for the said breech block, a cartridge feed device situated in a magazine having an opening therein, a pivoted lever one end of which projects into the magazine through said opening the other end being bent downwardly and having a shoulder thereon which engages the breech closing spring when the magazine is empty said lever having a projection against which a spring bears to hold the pivoted lever out of engagement with the breech closing spring when the magazine is not empty. 120
10. Breech mechanism for automatic firearms comprising the combination with a breech block of a closing spring for the said breech block, a cartridge feed device and a pivoted lever one end of which projects into the magazine and has a braking surface which is pressed against the breech block by the breech closing spring engaged by the other arm of the said pivoted lever when the magazine is empty. 125
11. Breech mechanism for automatic firearms comprising the combination with a breech block of a breech closing spring, two knee-jointed levers pivoted to the breech block and to the breech casing respectively, the rear lever being coupled with the breech closing spring by means of a link chain, and a pivoted lever one arm of which engages the breech closing spring when the other arm is engaged by the cartridge feed device after having fed the last cartridge into the breech casing. 130

In witness whereof I have hereunto set my hand in presence of two witnesses.

HUGO BORCHARDT.
